CLAIM

The ornamental design for a speaker box, as shown and described.

DESCRIPTION

FIG. 1 is a front, top, right perspective view of a first embodiment of a speaker box showing my new design; FIG. 2 is a front elevational view thereof; FIG. 3 is a left side elevational view thereof; FIG. 4 is a right side elevational view thereof; and FIG. 5 is a top plan view thereof.

FIG. 6 is a front, top, right perspective view of a second embodiment of a speaker box showing my new design; FIG. 7 is a front elevational view thereof; FIG. 8 is a left side elevational view thereof; FIG. 9 is a right side elevational view thereof; and, FIG. 10 is a top plan view thereof.

Portions in broken lines are for illustrative purpose only and form no part of the claimed design. Dot-dash broken lines define the boundaries of, but not included in, the claimed design.

1 Claim, 10 Drawing Sheets
